No Drawing. 7 Pages Specification

Certain aralkanols represented by the formula

wherein:

C_nH_{2n-1} is a saturated hydrocarbon chain;
 n represents an integer selected from 1 to 4;
 X , Y and Z individually represent chloro, bromo or nitro; and
 m , m' and m'' each represent an integer selected from 0 to 3, provided that the sum of $m+m'+m''$ equals at least 2,

are prepared by reacting a naphthaldehyde with a Grignard reagent. The aralkanols effectively control the growth of gram-positive microorganisms.
